UNITED STATES PATENT OFFICE.

GEORGE E. MOLYNEUX, OF BAYONNE, NEW JERSEY.

SPEED-GOVERNED STOPPING MECHANISM.

1,321,118.

Specification of Letters Patent.

Patented Nov. 11, 1919.

Application filed August 31, 1915. Serial No. 48,191.

To all whom it may concern:

Be it known that I, GEORGE E. MOLYNEUX, a citizen of the United States, and residing in the city of Bayonne, county of Hudson, in the State of New Jersey, have invented certain new and useful Improvements in Speed-Governed Stopping Mechanisms, of which the following is a specification, reference being had to the accompanying drawings, 10 forming a part thereof.

The immediate purpose of this invention is to produce an improved mechanism for arresting quickly the motion of high speed sewing machines without shock or jar or un- 15 due wear, but the invention, as will be perceived, is applicable to other machines. In all stopping mechanisms of the same general character as that in which the present invention is embodied there is, of course, some 20 part the position or movement of which is determined or controlled by the speed of the machine to which the mechanism is applied; such part, by its position or movement, determining the operation of the stopping 25 devices so that such devices shall not become effective until the speed of the machine has fallen below a predetermined rate, which may be dependent upon the character 30 of the work being performed. In the earlier efforts to produce a stopping mechanism of this character reliance was placed upon a 35 movable dog which was held, by centrifugal force, at a speed above that predetermined for the operation of stopping devices, out of 40 the path of a stop, but was moved by a spring into the path of such stop as the speed fell below the predetermined rate. In such devices the movable dog moved gradually 45 into the path of the stop as the speed diminished, with the result that the dog was successively sheared off as the speed gradually diminished, so that the mechanism quickly became inoperative. In later forms of such mechanism, designed to overcome the difficulty just referred to, there were two parts, one of which was relatively fixed while the other was rotatable with the shaft, arranged 50 so that one of such parts might be moved, in an axial direction, into engagement of the other of such parts, by the action of a device acted upon by centrifugal force in opposition to a spring. These later forms proved to be successful in operation but they re-

quired rather strong springs, developed considerable friction between the relatively 55 movable parts, were somewhat complicated in construction, and were not so constructed that they could be applied readily to existing machines. The improved mechanism in which the present invention is embodied is 60 designed so as to overcome the difficulties incident to the use of both types of mechanisms referred to and so as to be complete in itself and capable of application without difficulty to existing machines. The particular form of the mechanism which has been chosen for illustration herein is designed 65 particularly for use with straight-away sewing machines as distinguished from machines which are intended to be stopped automatically after a given number of stitches. It is further designed so that it may be adjusted readily by the operator to insure the 70 arresting of the movement of the sewing machine with the needle-bar in its highest 75 position regardless of the character of the material being sewed. In accordance with the invention a radially movable block, carried with the rotating shaft and subject to the action of the centrifugal force supports, 80 at all speeds above the predetermined limit at which the stopping mechanism shall act, a radially movable but non-rotatable carrier 85 with a stop-lug out of the path of a co-acting shoulder which rotates with the shaft; and when the speed falls below the predetermined limit the centrifugal block yields to 90 spring pressure applied to the carrier and the stop-lug carried thereby is permitted to move into the path of the coacting lug on 95 the rotatable part. Suitable provision is made so that the maximum force is required to start the centrifugal block from its normal or inoperative position in order that the stop-lug shall be moved instantly, rather than gradually, into its full operative position and all shearing action be thereby avoided. The invention will be more fully explained hereinafter with reference to the 100 accompanying drawings in which is illustrated a convenient and practical embodiment of the invention, and in which,—

Figure 1 is a view in front elevation showing the improved stopping mechanism applied to the arm of the sewing machine.

Fig. 2 is a view of the same in end eleva-

tion as seen from the right hand in Fig. 1, with a portion of the driving pulley broken away to disclose the parts beyond it.

Fig. 3 is a view of the same parts in longitudinal section.

Fig. 4 is a view in section on the plane indicated by the line 4—4 of Fig. 3, looking in the direction of the arrow.

Fig. 5 is a perspective view of the central trifugal block.

Fig. 6 is a view of the mechanism partly in horizontal section and partly as seen from above.

Fig. 7 is a view in section on the plane indicated on the line 7—7 of Fig. 6, looking in the direction of the arrow.

The improved stopping mechanism is shown in the drawings as applied directly to the arm *a* of an ordinary sewing machine, the arm having the hub *a'* which furnishes a bearing for the usual shaft *b* and also serves, in conjunction with the shaft, as a support for the stopping mechanism. No other adaptation of any ordinary sewing machine than the shaping of this hub is necessary to permit the stopping mechanism to be applied thereto, so that such stopping mechanism may be made up as a unit complete in itself and sold directly to the user of the sewing machine to be applied thereto.

To permit the stopping mechanism to be applied directly to the arm of the sewing machine, and also to provide for the suitable cushioning of the stopping mechanism, there is first secured rigidly to the hub *a'*, as by means of a set screw *c'*, a ring *c*, which is provided at a suitable point with a radial lug *c²*. To the ring *c* is secured frictionally, and so as to be capable of a limited rotary movement, a disk *d*. As shown particularly in Figs. 6 and 7 this disk *d* is provided with arc-shaped slots *d'* through which headed screws *d²* are passed into the ring *c*, whereby the disk *d* is held frictionally against the fixed ring *c*. On the left hand face of the disk *d* are formed spring abutments *d³* and *d⁴*, between which stands the radial lug *c²* of the fixed ring *c*. A relatively heavy spring *e* is interposed between the radial lug *c²* and the abutment *d³* to cushion the stopping mechanism, and between the radial lug *c²* and the abutment *d⁴* is interposed a relatively lighter spring *e'* to cushion the recoil.

The usual hand wheel and driving pulley having been removed from the shaft *b*, there is substituted therefor a sleeve *f* which is secured rigidly to the shaft *b*, as by a set screw *f'*, and carries at one end the driving pulley *f²* and at the other end the disklike rotatable member *f³* of the stopping mechanism. This rotatable member *f³* is slotted radially, as shown at *f⁴* in Fig. 4, to receive the centrifugal block *g*, which is shown in detail in Fig. 5. This block is held nor-

mally in its outer position by a light spring *g'*, shown in Fig. 3, regardless of the position of the rotatable member *f³* or its speed. It is adapted to move in a truly radial direction with respect to the shaft *b* and rotatable member *f³*, so that its sides, for a portion of their length, are parallel, as at *g²*, while the sides of the radial slot *f⁴* are also parallel for a portion of their length, as at *f⁵*. The outer portions of the sides of the block *g*, however, are inclined toward each other, as at *g³* (that is, the block is tapered), and the outer portions *f⁶* of the sides of the radial slot *f⁴* are also inclined inwardly at the same angle, which is such that there can be no wedging action between the block and the sides of the slot; however, the portions *g³* of the sides of the block and the portions *f⁶* of the sides of the slot, being perfectly plane and smooth surfaces of metal, adhere slightly to each other when the block is in its extreme outward position, or are held together by atmospheric pressure, so that the maximum of pressure is required to start the block from its extreme outer position, while its continued movement is resisted only by the light spring *g'*. This is important to prevent the gradual inward movement of the detector pin, hereinafter referred to, and its possible shearing. The block *g* is retained in the slot *f⁴* by a keeper *f⁸*.

The extreme outer edge *g⁴* of the centrifugal block *g* is curved on the same radius as the disklike rotatable part *f³* and fills completely the gap formed by the slot in the periphery of the disklike rotatable part *f³*, and forms with such periphery a practically continuous and unbroken circular track. On this track, when the machine is rotating at a speed above the predetermined limit, rests a detector pin *h* which is preferably mounted yieldingly, by means of a stem *h'* and encircling spring *h²*, in a carrier *i*. The purpose in mounting the pin *h* yieldingly is to permit it to yield readily to any break in the continuous track on which it rests which might exist at the edge of the radial slot *f⁴*. This pin may be hardened as well as the peripheral track on which it rests, so that the friction between the two is negligible. The pin is guided readily in a radial aperture *d⁵* formed in the overhanging flange *d⁶* of the disklike member *d*.

The carrier *i*, which constitutes a device for coupling the relatively stationary member *d* and the rotatable member *f³* to arrest the motion of the latter, is guided for radial movement on the member *d* by radial slots *d⁷* and *d⁸* and carries the radial stop lug *i'* for coöperation with the corresponding stop lug *f⁷*, which is secured to the rotatable member *f³*. The carrier *i* receives the pressure of a spring *k* which tends to press the

carrier inward against the centrifugal block g and the spring is provided with an adjusting screw h , easily accessible, so that the pressure may be regulated according to the character of the work being performed. By adjusting the pressure of this spring it is possible to vary the limit of speed at which the stopping mechanism will operate, for if the pressure of the spring be increased 5 the detector pin h will overcome the centrifugal force which acts upon the block g , in addition to the spring g' , at a lower speed of rotation of the shaft than it would if the speed were higher. In this manner 10 it is possible to regulate the stopping mechanism according to the character of the fabric being sewed and the friction of the needle in passing through it so that the movement of the machine shall be arrested, as is desirable, when the needle-bar is in its highest position.

In order that the operator may start the machine, a fork m , having cam-fingers m' to engage pins i^2 on the sides of the carrier i , is mounted on the sleeve f so as to be movable in a longitudinal direction thereon, and is engaged by a bell-crank lever n which is connected in the usual manner, as by a spring n' and link n^2 , with the usual controlling treadle. A light spring o acts 25 against the fork m in opposition to the bell-crank n . Pressure of the operator's foot on the treadle effects the coupling of the transmission in the usual manner and at the same time actuates the bell-crank lever n to move the fork m against the spring o and cause the fingers m' to withdraw the carrier i and the stop lug i^2 so that the machine is free to operate, while release of the pressure of the 30 operator's foot causes the uncoupling of the usual transmission and the withdrawal of the fingers m' from underneath the pin i^2 so that the stop mechanism may operate as soon as the speed falls below the predetermined limit.

It will be understood that various changes may be made in the details of construction and arrangement to suit the different uses and convenience of the manufacturer without departing from the spirit of the invention.

I claim as my invention:

1. In a stopping mechanism, the combination of a relatively fixed member, a rotatable member, a centrifugal body mounted 55 movably on the rotatable member, and a coupling device mounted movably on one of said members to prevent relative rotation of said members and adapted to engage the other of said members, and held normally in inoperative position by said centrifugal body.

2. In a stopping mechanism, the combination of a relatively fixed member, a rotata-

ble member, a centrifugal body mounted 65 movably on one of said members, a coupling device mounted movably on one of said members and adapted to engage the other of said members to prevent relative rotation of said members and held normally in inoperative 70 position by said centrifugal body, and means to move said coupling device in opposition to the action of the centrifugal body.

3. In a stopping mechanism, the combination of a relatively fixed member, a rotatable member, a centrifugal body mounted 75 movably on the rotatable member, a coupling device mounted movably on one of said members and adapted to engage the other of said members to prevent relative 80 rotation of said members and held normally in inoperative position by said centrifugal body, a spring acting upon said coupling device to move the same in opposition to the action of the centrifugal body, and means to adjust the pressure of said spring.

4. In a stopping mechanism, the combination of a relatively fixed member, a rotatable member, a centrifugal body mounted 90 movably on the rotatable member, a coupling device mounted movably on one of said members and adapted to engage the other of said members to prevent relative rotation of said members and held normally in inoperative position by said centrifugal 95 body, and means to disengage said coupling device from the other of said members.

5. In a stopping mechanism, the combination of a relatively fixed member, a rotatable member, a centrifugal body mounted 100 movably on the rotatable member, a coupling device mounted movably on one of said members and adapted to engage the other of said members to prevent relative rotation of said members and held normally 105 in inoperative position by said centrifugal body, a device to withdraw the coupling device from engagement with the other of said members, means under the control of the operator to actuate said device in one 110 direction, and a spring to actuate said device in the opposite direction.

6. In a stopping mechanism, the combination of a relatively fixed member provided with means to permit limited movement 115 thereof, means to cushion such rotary movement, a rotatable member, a radially movable coupling device to connect one of said members with the other, and centrifugally controlled devices to control said coupling 120 device.

7. In a stopping mechanism, the combination of a collar adapted to be secured to the arm of a sewing machine co-axially with the shaft, and a stopping mechanism 125 secured to said collar and comprising a relatively fixed member co-axial with the shaft, a rotatable member co-axial with the

shaft, a centrifugal body mounted movably on the rotatable member, and a coupling device mounted movably on one of said members to prevent relative rotation of said members and adapted to engage with the other of said members, and held normally in inoperative position by said centrifugal body.

8. In a stopping mechanism, the combination of a relatively fixed member co-axial with the driven shaft, a disklike member secured to the driven shaft and having a radial slot, a centrifugal body mounted in said slot and normally filling the gap in the periphery of the disklike member, and a coupling device movable radially on the relatively fixed body and adapted to engage the disklike member to arrest the rotation of the shaft and held normally out of engagement therewith by said centrifugal body.

9. In a stopping mechanism, the combination of a relatively fixed member co-axial with the driven shaft, a disklike member secured to the driven shaft and having a radial slot with inwardly inclined sides, a centrifugal body mounted in said slot and having inwardly inclined sides and normally filling the gap in the periphery of the disklike member, and a coupling device movable radially on the relatively fixed body and adapted to engage the disklike member to arrest the rotation of the shaft and held normally out of engagement therewith by said centrifugal body.

10. In a stopping mechanism, the combination of a relatively fixed member co-axial with the driven shaft, a disklike member secured to the driven shaft and having a radial slot with inwardly inclined sides, a centrifugal body mounted in said slot and having inwardly inclined sides and normally filling the gap in the periphery of the disklike member, a coupling device movable radially on the relatively fixed body and adapted to engage the disklike member to arrest the rotation of the shaft and held normally out of engagement therewith by said centrifugal body, and a spring bearing on said coupling device to move the same in opposition to the action of the centrifugal body.

11. In a stopping mechanism, the combination of a relatively fixed member co-axial with the driven shaft, a disklike member secured to the driven shaft and having a radial slot and an abutment, a centrifugal body mounted in said slot and normally filling the gap in the periphery of the disklike member, and a carrier supported for radial movement on the relatively fixed body and having a stop lug adapted to engage said abutment, and having also a detector pin bearing on the periphery of said disklike member and the outer edge of the centrifugal body.

12. In a stopping mechanism, the combination of a relatively fixed member co-axial with the driven shaft, a disklike member secured to the driven shaft and having a radial slot and an abutment, a centrifugal body mounted in said slot and normally filling the gap in the periphery of the disklike member, a carrier supported for radial movement on the relatively fixed body and having a stop lug adapted to engage said abutment, having also a detector pin bearing on the periphery of said disklike member and the outer edge of the centrifugal body and holding the carrier with its stop lug out of engagement with said abutment, and a spring bearing on said carrier to move the same in opposition to the action of said centrifugal body.

13. In a stopping mechanism, the combination of a relatively fixed member co-axial with the driven shaft, a disklike member secured to the driven shaft and having a radial slot and an abutment, a centrifugal body mounted in said slot and normally filling the gap in the periphery of the disklike member, a carrier supported for radial movement on the relatively fixed body and having a stop lug adapted to engage said abutment, having also a detector pin bearing on the periphery of said disklike member and the outer edge of the centrifugal body and holding the carrier with its stop lug out of engagement with said abutment, a spring bearing on said carrier to move the same in opposition to the action of said centrifugal body, and means to adjust said spring.

14. In a stopping mechanism, the combination of a relatively fixed member co-axial with the driven shaft, a disklike member secured to the driven shaft and having a radial slot and an abutment, and a centrifugal body mounted in said slot normally filling the gap in the periphery of the disklike member, a carrier mounted for radial movement on the relatively fixed member and having a stop lug for engagement with said abutment, and having also a detector pin bearing normally on the continuous track formed by the periphery of the disklike member and the centrifugal body and holding the stop lug out of engagement with the abutment, said carrier having also a transverse pin, a cam-finger adapted to be thrust beneath said pin to withdraw the carrier, and means to move said cam-finger.

15. In a stopping mechanism, the combination of a relatively fixed member, a rotatable member, a radially movable coupling device to connect one of said members with the other to prevent relative rotation of said

members, and centrifugally controlled devices to control said coupling device.

16. In a stopping mechanism, the combination of a relatively fixed member, a rotatable member, and radially movable means actuated by a reduction in centrifugal force effected by the slowing down of the rota-

table member to effect an engagement between the relatively fixed member and the rotatable member for the purpose of preventing relative rotation of said members. 10

This specification signed this 26th day of August, A. D. 1915.

GEORGE E. MOLYNEUX.
